UNITED STATES PATENT OFFICE

FELIX O. DE CARIE, OF LOS ANGELES, CALIFORNIA

INCINERATOR

Application filed November 20, 1926. Serial No. 149,606.

This invention relates to incinerators such as are used by municipalities and large organizations for incinerating refuse.

In order that an incinerator completely burn the refuse economically it is necessary that there be an ample draft. In the ordinary incinerator the refuse tends to pack against the walls thereof, thus obstructing the draft. It is an object of this invention to provide an incinerator in which the refuse cannot pack against the wall thereof. In my invention the draft will be preserved and efficient burning will take place. I accomplish this object of my invention by providing the incinerator chamber with vertical piers which hold the refuse away from the wall. Since the temperature in the furnace is very high, the piers must be properly cooled to prevent their being burned out.

It is accordingly an object of this invention to provide an incinerator in which the piers are cooled by circulating air therethrough.

It is another object of the invention to provide an incinerator having piers which are air cooled.

The incinerator of my invention is adapted to handle wet materials such as garbage or sewage. I have found that it is desirable to drain the free liquid from this refuse before the refuse is introduced into the chamber of the incinerator.

It is accordingly one of the objects of this invention to provide an incinerator in which the free liquid of the refuse may be drained therefrom before the refuse passes into the incinerator chamber.

If wet refuse is dropped directly onto the fire, the fire is partly extinguished and improper combustion will take place.

It is an object of this invention to provide an incinerator in which wet or damp refuse is dried before it reaches the fire.

Another object of this invention is to provide an incinerator in which a new charge of refuse is retained in the upper part of the incinerator and when dried or partly dried is dropped to the lower part thereof where the fire is situated.

Another object of this invention is to provide an incinerator having movable fuel sup-

porting members for supporting the refuse in the chamber during drying.

Another object of the invention is to provide an incinerator having fuel supporting members formed with air intake passages open to the exterior and communicating with the interior thereof through openings arranged adjacent the inner ends of said members for the passage of air to cool said members and to promote combustion.

Because of the nature of the material being burned in incinerators, the products of combustion usually carry odorous gases which are carried to the atmosphere producing a pungent stench.

It is accordingly one of the objects of this invention to provide an incinerator in which the odorous gases are condensed from the products of combustion.

A further object of the invention is to provide an incinerator in which dry combustible refuse may be dropped directly to the bottom of the incinerator directly to the fire.

A still further object of the invention is to provide an incinerator having an improved shaking grate.

Other objects and advantages of the invention will be made evident in the following description.

Referring to the drawings in which I illustrate my invention,

Fig. 1 is a vertical view partly sectioned of a preferred form of the invention.

Fig. 2 is a vertical section taken on the line 2—2 of Fig. 1.

Fig. 3 is a horizontal section taken on the line 3—3 of Fig. 1.

Fig. 4 is an enlarged fragmentary view of the shaking grate of the invention.

Fig. 5 is a section taken on the line 5—5 of Fig. 4.

Fig. 6 is a vertical section through a third form of the invention.

Fig. 7 is a section taken on the line 7—7 of Fig. 6.

Fig. 8 is an enlarged fragmentary section showing a water-cooled fuel supporting arm of the invention.

Referring to Figs. 1 to 5 inclusive, the preferred form of the invention will be de-

scribed. The numeral 20 represents the furnace of the incinerator, this furnace providing a chamber 23. The chamber 23 is divided into a lower fire or combustion chamber 22, a secondary treating chamber 21^a superposed above said combustion chamber and a primary treating chamber 21 superposed above said secondary treating chamber. Connected to the upper part of the chamber 21 is a conduit or exit flue 25 which is connected to a stack 24. At the lower part of the furnace 20 are shaking grates 26 which define the lower end of the fire chamber 22. The shaking grates 26 are shown in detail in Figs. 4 and 5. The shaking grates 26 are provided at their ends with trunnions 28 which are pivoted to longitudinal bars 29 supported by the furnace 20. Referring to Fig. 1, two of the bars 29 are supported by the main walls of the furnace 20 and two of the bars are supported by a central beam 30 of the furnace. Attached to the shaking grates 26 near the free ends thereof are links 33, these links being pivotally attached to the shaking grates by pivots 34. The lower ends of the links 33 are pivotally attached by pivots 35 to a longitudinal connector bar 36. The connector bars 36 are provided with rollers 37 which are adapted to run in longitudinal channels 38. Attached to one end of the connector bars 36 is a cross bar 39 to which an operating rod 40 is attached. When the operating rod 40 is in the position shown in Fig. 4, the shaking grates 26 are in normal or supporting position. The rod 40 may be moved in a direction indicated by the arrow 41 so that the shaking grates 26 are moved into dumping positions as indicated by dotted lines 42 of Fig. 4. When in the position indicated by dotted lines 42, the ashes and coals or any other residue are dumped from the fire chamber 22. When it is desired to remove some of the ashes therefrom this is accomplished by moving the shaking grates 26 a small distance from normal position in rapid succession so that the fuel in the fire chamber will be agitated. The operating rod 40 may be operated by a piston 44 which is placed in a cylinder 45. The piston 44 can be moved back and forth by hydraulic pressure applied to the cylinder 45. Refuse is supplied to the chamber 23 by means of hoppers 50 provided at the upper end of the furnace 20. Each hopper 50 has diagonal side walls 51 which converge in a downward direction. End walls 52 of each hopper 50 are vertical. Attached to the end walls 52 are slides 53 which may be formed from angle irons as shown. These slides 53 extend from the side walls 51 and meet at a central point. This is clearly shown in Fig. 1. Adapted to operate on the slides 53 are doors 55, there being a door 55 resting on each slide 53. The doors 55 are hinged together at 56 and are supported by a vertical operating rod 57. When the doors are in the position shown in

Figs. 1 and 2 they close the opening in the bottom of the hopper. By elevating the rod 57 the doors 55 may be moved into a position indicated by dotted lines 59 so that the bottom of the hopper is open. Each of the hoppers has the side walls provided with perforations 61 which connect to drain spaces 62. The drain spaces 62 have liquid drain pipes 63 connected thereto. When very wet refuse is placed in the hoppers 50, any free liquid may drain therefrom through the openings 61 and into the spaces 62. The drained liquid passes from the spaces 62 through the pipes 63 to a suitable point of disposal.

For the purpose of supporting the refuse when it is dropped into the chamber 23 from the hoppers 50 I provide primary upper and secondary lower fuel supporting means indicated by numerals 66 and 67. The lower fuel supporting means 67 defines the lower extent of the secondary treating chamber 21^a and the upper extent of the fire chamber 22, and the upper fuel supporting means 66 defining the lower extent of the primary treating chamber 21 and the upper extent of the secondary treating chamber 21^a. The upper and lower fuel supporting means are identical so that a description of one will suffice for both. Placed in opposing side walls 68 of the furnace are bearings 69. Extended through the bearings 69 are fuel supporting arms 70. The fuel supporting arms 70 shown in Figs. 1 to 3 are provided with air inlet passages 71. The outer ends of the passages 71 are open to the atmosphere and the inner ends are connected to the chamber 23 by small openings 73 which are formed in the extreme inner pointed ends of the arms 70 on the lower sides thereof, said pointed inner ends permitting the arms to be forced more readily inwardly through such material as may be in their path of movement. It should be noted that the arms of the upper and lower supporting means are divided into piers which extend into the chamber 23 from the opposite sides thereof. These arms may be moved from positions similar to which the lower arms 67 in Fig. 1 occupy, into positions similar to which the upper arms 66 in said Fig. 1 occupy. The moving of these arms is accomplished by the following mechanism.

Each of the arms 70 is provided with a rack 76 at the outer end thereof. Adapted to engage each rack 76 is a pinion 77 mounted on a shaft 78. There are four shafts 78, one for each set of arms 70. Each shaft 78 is supported by a bearing bracket 79. Attached to one end of each shaft 78 is a pinion 80 which is engaged by a rack 81. Each rack 81 is formed on the end of a piston rod 82 which extends into a cylinder 83. A piston 84 is attached to the inner ends of each of the rods 82 and is adapted to be operated in its cylinder 83 by hydraulic pressure placed

thereon. Hydraulic pressure may be placed on either side of the pistons 84 by pipes 86 which connect to the cylinders 83 at opposite ends. It will be seen that when the pistons 84 are moved, the racks 81 are moved so that the shafts 78 are rotated. The pinions 77 carried and rotated by the shaft 78 move the rack 76 so that the arms 70 are moved inward or outward according to the direction of rotation of the pinions 77. Each set of arms 70 is operated by a separate hydraulic means so that refuse dropped into the chamber 21 from the hopper may be lowered to the fire chamber 22 by operating the arms 70. Placed in the chamber 23 and extending through both treating chambers are vertical piers 90 which are provided for the purpose of preventing the refuse from packing against the walls of the chamber 23, thus destroying the draft. The piers 90 provide draft spaces 91 therebetween. The piers shown in Figs. 1 to 3 are composed of sheet metal and have circulating spaces 92 formed therethrough. The upper ends of the piers 90 are connected to the upper part of the preparing chamber 23. The upper ends of those piers 90 adjacent to the conduits 25 serve as baffles to prevent the refuse from passing into the conduits. Openings 94 are provided in these piers 90 which connect to the conduit 25 for accelerating the draft. The lower ends of the piers 90 terminate immediately above the lower fuel supporting means 67 and are provided with horizontal legs 96 which extend outward through the furnace 20 and communicate the lower ends of the draft passages 92 to the exterior. Cooling air is drawn into the lower ends of the piers 90, this cooling air passing from the upper ends thereof into the upper part of the primary treating chamber 21 and through the conduits 25. The air is caused to circulate through the piers 90 by reason of the fact that the piers are heated and thus the air therein is heated and caused to move upward. This draws additional cool air into the piers and prevents them from overheating.

Referring particularly to Fig. 1, in the stack 24 I provide a means for condensing the odorous gases from the products of combustion. This means has a pan 100 which has a central opening 101 and provides an annular trough 102. Supported above the pan 100 by a vertical arm 101^a is a dome 103. Extended through the wall of the stack 24 is a liquid supply pipe 105 which is adapted to drop fluid onto the apex of the dome 103. The water flows down the upper face of the dome 103 and into the trough 102. The water falls in the form of an annular film through which any gas passing through the stack 24 must pass. The liquid fills the trough 102 and overflows, passing through the opening 101 in an annular film. Any gases passing through the stack must also

pass through this second film. Any odorous gases carried with the gases of combustion are condensed when they strike the films of water and drop with the water to the lower part of the stack. The lower part of the stack is provided with a chamber 107 in which the water may cool. When the water reaches a certain height it may pass from the stack through an overflow pipe 108. The operation of this form of the invention is substantially as follows:

In starting up the incinerator it is necessary to place combustible material in the fire chamber. Referring to Figs. 2 and 3, it will be seen that near one end of the furnace there are no fuel supporting arms 70. Combustible material placed in the left hopper 50 in Fig. 2 will drop directly to the fire chamber 22. Refuse which is damp or otherwise not in condition for combustion is placed in the right hopper 50. The upper fuel supporting means 66 is moved into the position indicated by dotted lines 112 of Fig. 1. The refuse is retained in the right hopper for a short period of time so that any free liquid may drain therefrom, as previously explained. The lift rod 57 is then pulled upward and the doors 55 are moved into open position. The refuse drops into the upper part of the preparing chamber 23, being supported by the upper arms 70. The fire, having been started in the fire chamber 22, evaporates the moisture in the refuse retained in the treating chambers in the upper part of the chamber 23. When this charge of refuse has been partly dried, the upper arms 66 are returned to the positions shown by full lines in Fig. 1. This permits the partly dried charge to drop onto the lower fuel supporting means 67. Immediately after this, the upper fuel supporting arms 66 are returned to dotted line position and a new charge is dropped thereonto. The lower fuel supporting arms 67 are then retracted into positions indicated by dotted lines 114 of Fig. 1. After it has dropped onto the lower fuel supporting means 67 the charge of refuse becomes prepared for burning, and when the arms 67 are retracted into the positions indicated by dotted lines 114 part of the charge will drop into the fire chamber 22. The charge will continually drop into the fire chamber as the fuel already in the fire chamber burns away. In case of jamming of any sort, the lower fuel supporting means may be moved back and forth, thus loosening the charge and causing it to fall into the fire chamber. When the charge in the lower treating chamber 21^a has been entirely dropped into the fire chamber 22, the lower fuel supporting means 67 is returned to the position shown by full lines, and the upper fuel supporting means 66 is moved to the full line position, thus dropping the upper charge onto the lower fuel supporting means. The vertical piers 90, as

previously explained, prevent the refuse from packing against the walls of the furnace 20.

This evaporation of moisture from the suspended refuse is effected rapidly and thoroughly by reason of the particular arrangement of the elements constituting the furnace. It will be evident that if the treating chamber did not have the vertical piers 90 and draft passages 91 and was filled with a mass of damp refuse, all of the products of combustion and all of the vapors generated in the lower portion of the mass adjacent the fire, would, to reach the exit flue, have to travel through the entire damp mass. It has been found that such vapors will start to condense at a very small distance above the bottom of the mass and that before having traveled to any considerable extent through the moist mass they will be fully condensed, this condensate together with additional moisture combined therewith in the process of condensation, drops towards the heating zone and in a short time this vaporization and condensation will reduce the mass to a wet compact mass incapable of being dried and burned by the heat available in the furnace; in fact such wet compact mass will cut off the draft of the furnace to such an extent as to smooth the fire and with certain characters of refuse the returning moisture is at times of such volume as to drip from said mass and put out the fire.

In the present apparatus, this undesirable condition is eliminated by insuring an immediate escape of the vapors or an escape thereof before condensation can take place.

This is the major function of the piers 90 and draft passages 91 which cooperate with the horizontal arms 67 to insure a certain draft condition which will insure the desired result. As the draft passages 91 extend from the top of the combustion chamber 22 to the exit flue at the top of the furnace the products of combustion in the chamber 22 will flow therethrough direct to the exit flue, thus creating a pronounced upward draft surrounding the refuse. This will convey any gases or vapors given off from or conveyed to the outer periphery of the refuse mass at any level, directly to the exit flue. As the refuse on the arms 67 is dried said arms are retracted gradually and the dried refuse will enter the combustion chamber as the material therein is consumed, and as the retraction of said arms creates an open space above the center of the combustion chamber the fire will advance into such central open space and form an arch-shaped burning mass in the center of the furnace just above the arms 67, which burning mass will create a high temperature zone in the lower center of the secondary treating chamber, gradually becoming wider as the arms 67 are retracted. By reason of this and the disposition of the

draft passages 91, the higher temperature products of combustion and the produced vapors are drawn laterally through the lower layer of the refuse resting on the arms 67 directly to the passages 91, thus disposing of said vapors before they have had time to condense. This action is materially assisted by the volume of free air entering said zone through the ports 73 of the arms 67.

As shown in the plan view of Fig. 3, draft spaces 91 are provided between adjacent piers 90 through which the draft may pass. In the incinerator of this invention it is absolutely impossible for the draft to be destroyed. The fuel supporting arms 70 are cooled in this form of the invention by a current of air which passes inward through the air inlet passages 71 thereof. The draft of the furnace pulls the air through the opening 73 at the inner ends of the supporting arms 70, thus creating the current of air which cools said arms and also tends to promote better combustion in the furnace. The vertical piers 90 are prevented from overheating and burning out, by a current of air which is induced therethrough by the heating of the piers. As previously explained, the heating of the piers heats the air therein, causing it to move upward. This draws cool air into the lower ends of the piers and thus the circulation is established. The ashes may be removed from the fire chamber 22 by operating the shaking grates 26. This is accomplished by operating the piston 44 in the cylinder 45, as previously explained. The gases of combustion and any gases formed from the refuse are drawn promptly into the draft passages 91 and pass through the conduits 25 into the lower end of the stack 24. The gases must pass through the device of the invention for condensing the odorous gases therefrom. As previously explained, the gases must pass through two films of water before they can pass outward from the stack 24. The contact of the gases with the water condenses any of the odorous gases carried by the gases of combustion. The films of water also collect any fine solid particles which may be carried in the gases of combustion.

In Figs. 6, 7, and 8, I illustrate a third form of the invention. This form of the invention has a furnace 150 which consists of an inner shell 151 and an outer shell 152, there being a space 153 provided between these two shells through which water may be circulated by pipes 155 and 156. The water circulated through the space 153 prevents an overheating and a burning out of either of the shells, particularly the inner shell 151. The furnace 150 provides a large chamber 157, to the upper end of which is connected a refuse inlet opening 158. The upper end of the inlet opening 158 is closed by a lid 159. At the lower part of the chamber 157 are shaking grates 162 which are identical with the shak-

ing grates 26 provided in the first form of the invention. Since the construction is identical, the construction of the shaking grates 162 need not be described. This form of the invention like the first form includes an upper fuel supporting means 164 and a lower fuel supporting means 165. The upper and lower fuel supporting means have fuel supporting arms 168 which extend into the chamber 157 from the opposite sides thereof. The fuel supporting arms 168 are constructed substantially the same as the fuel supporting arms 70.

As illustrated in Fig. 8, thimbles 170 are extended through walls of the furnace 150, these thimbles providing bearings 171 for the arms 168. The inner ends of the arms 168 have no openings as were provided in the arms 70. Attached to the outer ends of the arms 168 are heads 173 from which septums 174 extend. The septums 174 extend to the inner ends of the arms 168 dividing them into passages 176. Connected to the heads 173 below the septums 174 are pipes 178 and connected to the heads 173 above the septums 174 are pipes 179. The pipes 179 are connected to inlet headers 180 and the pipes 178 are connected to outlet headers 181. Referring to Fig. 7, the inlet headers 180 which are arranged on opposite sides of the furnace have inwardly extending legs 183. These legs 183 extend through stuffing boxes 184 into a barrel 185. Cooling fluid, such as water, is supplied to the interior of the barrel 185 by means of a pipe 186. This fluid passes into the ends of the legs 183, through the inlet headers 180, through the pipes 179 and into the upper passages 176 of the arms 168. The outlet headers 181, which are located below the inlet headers 180, are provided with legs 188 which extend through stuffing boxes 189 into a barrel 190. Water is conducted from the barrel 190 by means of a pipe 191. The water passes inward through the upper passages 176 around the ends of the septums 174 and outward through the lower passages 176. The water then passes through the pipes 178, the outlet header 181, the legs 188, and into the barrel 190, the water being conducted from the barrel through the pipe 191. This form of the invention is provided with vertical piers 200 which are provided for the purpose as in the other forms of the invention, preventing the refuse from packing against the wall and thus destroying the draft. In this form of the invention the piers 200 are formed integrally with the inner shell 151. The inner shell 151 is provided with inwardly extending walls 202, the inner ends of which are connected together by walls 203. This structure forms the piers 200. It should be noted that in this form of the invention the piers 200 are cooled by the same water which is circulated through the space 153 between the shells 151 and 152.

In the form of the invention which I am now describing, the cooling is accomplished not by a flow of air but by a flow of liquid such as water through the different parts of the invention. The operation of the upper and lower fuel supporting means 164 and 165 is similar to that in the first form of the invention. Referring to Fig. 6, the arms 168 are provided with racks 206 which are engaged by pinions 207. The pinions 207 are mounted on shafts 208 which extend across the sides of the furnace. It should be noted that there are four shafts 208, one for each series of arms 168. The shafts 208 are supported by suitable brackets 210 as illustrated. In this form of the invention the arms 168 are not operated by hydraulic means but by manual means. The lower shafts 208 are provided with cranks 211. The upper shafts 208 are provided with sprockets 213 over which operating chains 214 extend. The chains 214 are provided so that the upper shafts 208 may be rotated from the floor.

In the foregoing description of the construction and operation of the form of my invention the important features have been thoroughly explained. These important features may be recapitulated as follows:

One feature of the invention is the provision of the vertical piers for preventing the refuse from packing against the wall of the incinerator, thus destroying the draft. This is quite important since if the draft is destroyed the fuel will not be burned properly. It is quite important that these piers be placed close to the wall of the furnace and preferably against the walls of the furnace as illustrated in the drawings.

Another feature of the invention is the means for cooling the piers. This may be either a circulation of air or a circulation of water through them.

The feature of draining the liquid from the refuse before it is introduced into the furnace is important since the free liquid is in this way disposed of and there is no danger of its flowing onto the fire. A very important part of the invention is the adjustable fuel supporting arms, by means of which the charges may be dropped, at proper times when they are properly dried, into the fire chamber. The feature of removing the odorous gases from the products of combustion of the incinerator is highly important. It is believed that this part of the invention is useful in other types of incinerators or furnaces than the ones illustrated in the drawings.

In the foregoing description I have illustrated various forms of the invention. It should be understood, however, that the invention may be embodied in different forms of construction without violating the scope of the invention.

I claim as my invention:

1. In an incinerator of the nature disclosed, the combination of: a furnace having a lower combustion chamber, a treating chamber superposed above said combustion chamber and an exit flue leading from the upper portion of said treating chamber, whereby all of the products of combustion must pass through said treating chamber; means for introducing into the upper end of the treating chamber, material to be consumed; material supporting means defining the upper extent of the combustion chamber and the lower extent of the treating chamber, said means consisting of opposed series of horizontal arms mounted to slide into and out of the furnace chambers while either or both chambers are filled with said material; and means for reciprocating said arms, there being draft passages disposed around said treating chamber and extending from said supporting arms upwardly to communication with said exit flue and serving to direct the products of combustion through the peripheral portion of said treating chamber so that the draft so created will draw vapors and gases from any level of said treating chamber directly to said exit flue.

2. A combination as defined in claim 1 in which the draft passages are formed by vertical piers disposed near the wall of the treating chamber, the piers serving to prevent packing of the material against said wall.

3. A combination as defined in claim 1, in which the draft passages are formed by vertical hollow piers disposed near the wall of the treating chamber, the lower ends of said piers terminating above said combustion chamber and communicating with the exterior of the furnace and their upper ends being in communication with the upper end of said treating chamber.

4. In an incinerator of the nature disclosed, the combination of: a furnace having a lower combustion chamber, a treating chamber superposed above said combustion chamber and an exit flue leading from the upper portion of said treating chamber, whereby all of the products of combustion must pass through said treating chamber; means for introducing into the upper end of the treating chamber, material to be consumed; material supporting means defining the upper extent of the combustion chamber and the lower extent of the treating chamber, said means consisting of opposed series of horizontal arms mounted to slide into and out of the furnace chambers while either or both chambers are filled with said material; and means for reciprocating said arms.

5. A combination as defined in claim 4, in which the inner ends of said horizontal arms are pointed so that they may be forced inwardly through material contained in said furnace.

6. A combination as defined in claim 4, in which said horizontal arms are provided with air intake passages open to the exterior of the furnace and communicating with the interior thereof through openings formed near the inner ends of said arms, the air passing through said intake passages serving to cool said arms and to promote combustion.

7. In an incinerator of the nature disclosed, the combination of: a furnace having a lower combustion chamber, a secondary treating chamber superposed above said combustion chamber, a primary treating chamber superposed above said secondary treating chamber, and an exit flue leading from the upper portion of said primary treating chamber, whereby all of the products of combustion must pass through both treating chambers; means for introducing into the upper end of said primary treating chamber, material to be consumed; primary material supporting means defining the upper extent of said secondary chamber and the lower extent of said primary chamber; secondary material supporting means defining the upper extent of said combustion chamber and the lower extent of said secondary chamber, each of said means consisting of opposed series of horizontal arms mounted to slide into and out of the furnace chambers while either or both adjacent chambers are filled with said material; and means for reciprocating said arms, there being draft passages disposed around said treating chambers and extending from said secondary supporting arms upwardly to communicate with said exit flue and serving to direct the products of combustion through the peripheral portions of both treating chambers so that the draft so created will draw vapors and gases from any level of either of said treating chambers directly to said exit flue.

8. A combination as defined in claim 7 in which the draft passages are formed by vertical hollow piers disposed near the walls of both treating chambers, the lower ends of said piers terminating above said combustion chamber and communicating with the exterior of the furnace and their upper ends being in communication with the upper end of said primary treating chamber.

9. In an incinerator of the nature disclosed, the combination of: a furnace having a lower combustion chamber, a secondary treating chamber superposed above said combustion chamber, a primary treating chamber superposed above said secondary treating chamber, and an exit flue leading from the upper portion of said primary treating chamber, whereby all of the products of combustion must pass through both treating chambers; means for introducing into the upper end of said primary treating chamber, material to be consumed; primary material supporting means defining the upper extent

of said secondary chamber and the lower extent of said primary chamber; secondary material supporting means defining the upper extent of said combustion chamber and the lower extent of said secondary chamber, each of said means consisting of opposed series of horizontal arms mounted to slide into and out of the furnace chambers while either or both adjacent chambers are filled with said material; and means for reciprocating said arms.

10. In an incinerator of the class described, the combination of: a furnace having a fuel treating chamber; means for introducing fuel into said chamber; a stack for said furnace; a conduit connecting said chamber and stack; fuel supporting means extended into said furnace, said fuel supporting means being provided in the form of horizontal arms 15 extended into said furnace from opposite sides, said arms having passages extending therethrough communicating with the atmosphere at their outer ends and with the interior of said chamber at their inner ends, 20 so that the draft of said incinerator will draw air through said arms; vertically disposed hollow piers connected to the walls of said chamber and having their lower ends terminating above said fuel supporting arms, 25 the upper ends of said piers having openings communicating with said conduit; and means for moving said supporting arms to deposit the fuel into the lower part of said furnace.

11. In an incinerator of the class described, 30 the combination: a furnace having a fuel treating chamber; means for introducing fuel into said chamber; a stack for said furnace; said furnace having a conduit leading to said stack; fuel supporting means comprising hollow arms extended into said furnace from opposite sides, said arms opening to the atmosphere at their outer ends and to 35 said chamber at their inner ends, so that the draft of said furnace will draw air through said arms; vertically disposed hollow piers connected to the walls of said treating chamber and having their lower ends open to the atmosphere and their upper ends communicating with said conduit; and means for 40 moving said arms to deposit fuel into the lower part of said furnace.

12. In an incinerator of the nature disclosed, the combination of: a furnace having a lower combustion chamber, a treating chamber 45 superposed above said combustion chamber and an exit flue leading from the upper portion of said treating chamber, whereby all of the products of combustion must pass through said treating chamber; means for introducing into the upper end of the treating chamber, material to be consumed; material supporting means defining the upper extent of the combustion chamber and the lower extent of the treating chamber, said 50 means consisting of opposed series of hori-

zontal arms mounted to slide into and out of the furnace chambers while either or both chambers are filled with said material, said arms being provided with air intake passages open to the exterior of said furnace and communicating with the interior thereof through openings arranged adjacent the inner ends of said arms, the air passing through said intake passages serving to cool said arms and to promote combustion; and means for reciprocating said arms.

13. In an incinerator of the nature disclosed, the combination of: a furnace having a lower combustion chamber, a secondary treating chamber superposed above said combustion chamber, a primary treating chamber superposed above said secondary treating chamber, and an exit flue leading from the upper portion of said primary treating chamber, whereby all of the products of combustion must pass through both treating chambers; means for introducing into the upper end of said primary treating chamber, material to be consumed; primary material supporting means defining the upper extent of said secondary chamber and the lower extent of said primary chamber; secondary material supporting means defining the upper extent of said combustion chamber and the lower extent of said secondary chamber, each of said means consisting of opposed series of horizontal arms mounted to slide into and out of the furnace chambers while either or both adjacent chambers are filled with said material, said arms being provided with air intake passages open to the exterior of said furnace and communicating with the interior thereof through openings arranged adjacent the inner ends of said arms, the air passing through said intake passages serving to cool said arms and to promote combustion; and means for reciprocating said arms.

In testimony whereof, I have hereunto set my hand at Los Angeles, California, this 15th day of November, 1926.

FELIX O. DE CARIE.
